UNITED STATES PATENT OFFICE.

WILLIAM E. BARLOW, OF TREVOSSE, PENNSYLVANIA, ASSIGNOR TO HENRY A. DYGERT,
OF PHILADELPHIA, PENNSYLVANIA.

SWAGING MACHINE.

Application filed October 6, 1923. Serial No. 666,930.

To all whom it may concern:

Be it known that I, WILLIAM E. BARLOW, a citizen of the United States, residing at Trevose, county of Bucks, and State of Pennsylvania, have invented certain new and useful Improvements in Swaging Machines, of which the following is a specification, reference being had to the accompanying drawings.

10 My invention relates to machines useful for swaging articles of annular formation, and more particularly to a type adapted to swaging bands formed of sheet material such for example as paper, card board or metal.

15 The primary object of my invention is to provide a machine capable of swaging articles of the character described in a continuous and rapid manner with assurance 20 of perfect uniformity in the results attained.

25 The detailed description which follows of a typical embodiment of my invention will serve to make obvious other objects and attendant advantages, while the claims define the scope of my invention in so far as it is at present known to me.

30 In the drawings, Fig. I is a perspective view of the swaging machine of my invention.

Fig. II is a plan view of the same with certain parts removed to avoid concealment of important details.

35 Fig. III is a detail sectional view taken as indicated by the arrows III—III in Fig. II.

Fig. IV is a similar view but on a slightly larger scale taken as indicated by the arrows IV—IV in Fig. II.

40 Fig. V is a plan view of the assemblage of Fig. IV with some of the parts in sectional elevation; and

45 Figure VI is an illustration showing a container having as one of its constituent elements an encircling band capable of being swaged by the machine of my invention.

50 As herein shown, the movable parts of my improved swaging machine are supported by a horizontal frame 1, preferably of structural steel sustained at a convenient height from the floor by a group of standards 2 suitably tied and braced to lend the requisite rigidity to the structure. Journalled in ap-

propriate bearings 3 adjacent one end of the frame 1 is a transverse shaft 4 whereto is secured, at one extremity, a support for the articles being swaged in the form of a head 5 of annular configuration with a polygonal periphery affording a multiplicity of faces 6, which are centrally apertured and screw-threaded to receive replaceable bushing cups 7 for accommodating and guiding radially 60 slidable plunger holders 8. Normally these plunger holders 8 protrude beyond the periphery of the head 5 to serve as supports 65 for the bands "B" (Figs. I, IV, V and VI) during swaging which is accomplished by cooperative action of a swaging die 9 whereto said bands are successively presented as 70 the head 5 is progressively rotated. In accordance with my invention immediately after swaging, the plunger holders 8 are successively retracted into the head 5 thereby to doff the swaged bands, which, upon being released, drop into an underlying collecting receptacle 10, appropriately supported by the substructure of the frame 1. Retraction of the plunger holders 8 is automatically effected through aid of compression springs 11, which individually encircle 75 the ends of reduced axial prolongations or stems 12 of said plunger holders that protrude inwardly through the bases of the cup guides 7. The springs 11 exert their influence against collars 13 adjustable along 80 the threaded portions of the stems 12 and capable of being fixed in adjusted positions by nuts 15—16 of which the latter are rounded so as to ride easily about the periphery of a cam 17 disposed within the hollow 85 of the head 5. This cam 17 is supported by studs 18 projecting inwardly from a longitudinal bar 19 of the frame 1, as best shown in Fig. V, and thereby held against rotation though traversed by the end of 90 shaft 4. The cam 17, it will be noted, is substantially of spiral configuration with a decided notch at 20, permitting recession of the plungers 8 under the action of the springs 11.

100 Any suitable means may be employed for imparting stepwise rotation to the head 5, one such means being herein exemplified as a pawling mechanism which includes a ratchet wheel 21, that is fixed to the shaft 4 105 and arranged to be picked by a pawl 22 on

the outer end of an arm 23 free to oscillate on said shaft. Rocking movement is imparted to the arm 23 through a link connection 24 with a crank 25 on the inner end 5 of a shaft 26 which is journalled in bearings 27 near the extremity of the frame 1 remote from that occupied by the shaft 4. Intermediate the bearings the shaft 26 carries tight and loose pulleys 28, 29 between which 10 a driving belt may be shifted as required by a shifter 30 capable of being actuated through the medium of a hand lever 31 terminating in a handle 32 at the opposite end of the machine.

15 Referring again to the swaging die 9, it will be noted that the same has its face recessed as at 35 so as to telescopically engage over the end of the plunger holders 8 in the head 5 as shown to best advantage 20 in Figs. IV and V, thereby to swage the interposed band "B," the overlapping portions 25 of the die and the plunger holders 8 being appropriately rounded or otherwise configured to produce the desired swaging effect. This swaging die 9 is secured to one end of a longitudinally reciprocatory rod 36 mounted in slide bearings 37-38, and held against rotation through provision 30 of a spline or feather 39. The rod 36 derives reciprocatory motion, in timed relation to the progressive shifting of the head 15, from a rotary cam 40, fixed to the outer end of the pulley shaft 26, which is effective upon an anti-friction roller 41 on a collar 42 which is secured to the proximate end of 35 said rod. The roller 41 is at all times maintained in operative contact with the cam 40 by a number of springs 43 interposed between the collar 42 already referred to and another collar 44, free on the rod 36 and abutting against the slide bearing 38.

40 As a means for ensuring maintenance of accurate alignment and registry of the plunger holders 8 relative to the swaging die 9 during the successive swaging operations, I employ a locking pin 45 (see Fig. V) which successively enters apertures 46 in the side face of a lateral annular flange 47 on the head 5, said apertures being uniformly spaced circumferentially, and corresponding in number to the plunger holders 8. The locking pin 45 is longitudinally slideable in a direction toward and away from the head 5, and guided in the boss 48 of a bracket 49 bolted or otherwise secured to the frame 1. One end of the locking pin 45 has an axial cavity so as to be capable of telescopically engaging a fixed horizontal stud 50 which assists guidance of said pin, 45 the cavity also accommodating a compression spring 51 that is effective to yieldingly urge the pin outward. Preparatory to each shifting of the head 5, the locking pin 45 is retracted by means of a slide bar 52 whereof 50 one extremity is beveled, as at 53 in Fig. II,

to afford a wedge cam designed to engage a roller 53 carried by said locking pin. The slide bar 52 is supported for longitudinal shifting jointly by the bracket 49 and a companion bracket 55, the former of these 55 affording anchorage for a headed stud 56 which projects through a slot 57 in said slide bar, see Fig. V. The function of actuating the slide bar 52 is vested in a rotary cam 58 which is mounted on the pulley shaft 26 immediately adjacent the cam 40 aforesaid and which is influential upon an anti-friction roller 59 on the contiguous end 75 of said slide bar.

80 In operation the rings or bands "B" to be swaged are successively mounted on the plunger holders 8 of the head 5, and, through motion of the latter, successively presented to the die 9 and swaging in a manner already explained. Charging of the head 5 may be greatly facilitated by installation of a hopper or receptacle such as shown at 60 in Fig. I wherein a quantity of the bands "B" can be stored. This hopper 60 has two of its adjacent side walls 61-62 cut away at one corner and its bottom 63 slightly downwardly inclined toward the head 5 at a convenient height so that the rings or bands "B" may be slid off at a level even with the plunger holders 8 and thus readily impaled upon the latter.

85 An instance suggestive of practical application of my invention is in connection with the manufacture of paper containers "S" such as represented, in Fig. VI wherein the swaged band "B" serves as a strengthening member as well as an ornamentation, about the container mouth, the inwardly turned or swaged edge "e" preventing displacement of said band through forced engagement with the conical surface of the container shell.

90 Having thus described my invention, I claim:

1. In a machine of the character described, the combination of a vertically rotatable support provided with bushing cups having radially slideable holders for the articles being swaged, a swaging die, and means for moving the support to successively present the articles to the swaging die. 110

115 2. In a machine of the character described, the combination of a vertically rotatable support fitted with replaceable bushing cups housing a series of radially slideable holders for the articles being swaged, a swaging die, and means for moving the support to successively present the articles to the swaging die. 120

125 3. In a machine of the character described, the combination of a vertically rotatable support fitted with replaceable bushing cups housing a series of radially slideable plungers for individual mounting of articles of annular configuration, a swaging die, and means 130

for moving the support to successively present the articles to the swaging die.

4. In a machine of the character described, the combination of a vertically rotatable support, a holder normally projecting radially from said support to sustain the article being swaged, a die adapted to swage the article on the holder, and means for retracting the holder into the support to doff the article after swaging.

5. In a machine of the character described, the combination of a vertically rotatable support, a holder normally projecting radially beyond the support to sustain the article being swaged, a die adapted to swage the article on the holder, and a cam associated with the holder instrumental in effecting retraction of the latter into the support for the purpose of doffing the article after swaging.

6. In a machine of the character described, the combination of a vertically rotatable support, a series of holders normally projecting radially from said support to sustain the articles being swaged, a swaging die, means for moving the support to successively present the articles to the swaging die, and means for successively retracting the holders into the support to doff the articles after swaging.

7. In a machine of the character described, the combination of a vertically rotatable support, a series of holders normally projecting beyond the support to sustain the articles being swaged, a swaging die, means for intermittently rotating the support to successively present the articles to the die, and a fixed cam adapted to be over-ridden by plungers at the inner ends of said holders during movement of the support, said cam having a recess permitting retraction of said plungers to successively doff the articles after swaging.

8. In a machine of the character described, the combination of a vertically rotatable support having bushing cups and radially slidable holders for the articles being swaged, a horizontally reciprocable swaging die, means for moving the support in timed rotation to successively present the articles to the swaging die, and a cooperative locking pin for arresting the support in successive shifted positions.

9. In a machine of the character described, the combination of a vertically rotatable support having bushing cups having a series of radially slidable projections for holding the articles being swaged, a horizontally reciprocable swaging die, and means for rotating the support in timed relation to successively present the articles to the swaging die.

10. In a machine of the character described, the combination of a vertically rotatable support having bushing cups hav-

ing a series of radially slidable projections for holding the articles being swaged, a horizontally reciprocable swaging die, and means for intermittently moving the support in timed relation to successively present the articles to the swaging die.

11. In a machine of the character described, the combination of a rotatable head, a series of radial holders normally projecting beyond the periphery of the head to sustain the articles being swaged, a swaging die, means for rotating the head to successively present the articles to the swaging die, a fixed cam with a recess adapted to be over-ridden by the inner ends of the holders during movement of the head, and springs operating to retract the holders into the head, as permitted by the recess of the cam to successively doff the articles after swaging.

12. In a machine of the character described, the combination of a rotatable hollow annular head, a series of radial holders normally projecting beyond the periphery of the head to sustain the articles being swaged, a swaging die, means for rotating the head to successively present the articles to the swaging die, a cam immovably supported within the hollow of the head and adapted to be over-ridden by the inner ends of the holders during movement of the head, and springs operating to retract the holders into the head, as permitted by the recess in the cam, to successively doff the articles after swaging.

13. In a machine of the character described the combination of a vertically rotatable support fitted with peripheral bushing cups having a series of radially directed spring influenced holders for the articles to be swaged, a horizontally reciprocable swaging die, means for intermittently rotating the support in timed relation to successively present the articles to the swaging die, and means for reciprocating said die relative to progressive shifting of the aforesaid support.

14. In a machine of the character described the combination of a vertically rotatable support fitted with bushing cups having a series of radially-directed spring influenced holders for the articles to be swaged, a horizontally reciprocable swaging die, means for intermittently rotating the support in timed relation to successively present the articles to the swaging die, and cam mechanisms effective to reciprocate said die relative to progressive movements of the support.

15. In a machine of the character described the combination of a vertically rotatable support fitted with bushing cups having a series of radially-directed spring influenced holders for the articles to be swaged, a horizontally reciprocable swaging die, means for intermittently rotating

the support in timed relation to successively present the articles to the swaging die, and a rotary cam effective to reciprocate said die in opposition to spring influence with timed relation to progressive movements of the aforesaid support.

In testimony whereof, I have hereunto

signed my name at Philadelphia, Pennsylvania, this 29th day of September, 1923.

WILLIAM E. BARLOW.
